UNITED STATES PATENT OFFICE.

FREDERIC N. PATTERSON, OF MARIANNA, ARKANSAS.

SHOE-PROTECTOR.

No. 820,250.

Specification of Letters Patent.

Patented May 8, 1906.

Application filed March 25, 1904. Serial No. 200,067.

To all whom it may concern:

Be it known that I, FREDERIC NORTON PATTERSON, a citizen of the United States, residing at Marianna, in the county of Lee, 5 State of Arkansas, have invented certain new and useful Improvements in Shoe-Protectors; and I do hereby declare the following to be a full, clear, and exact description of the invention, such as will enable others skilled in the 10 art to which it appertains to make and use the same.

This invention relates to shoe-protectors; and it has for its object to provide a simple and cheap article that may be easily and 15 quickly applied over the toe of the shoe to protect it from wear and which will be of such size and construction that it may be easily carried in the pocket when not in use.

The protector is particularly designed for 20 use by lumber inspectors to prevent wear of the toe of the shoe in kicking lumber, although it will be understood that it may be used under any conditions where the toe of the shoe is to be protected.

25 In the drawings forming a portion of this specification, and in which like numerals of reference indicate similar parts in the several views, Figure 1 is a perspective view of the protector, a shoe on which the protector is disposed being illustrated in dotted lines. Fig. 2 is a vertical section taken longitudinally through the toe portion of the protector. Fig. 3 is a detail sectional view showing the manner of attaching a buckle.

35 Referring now to the drawings, there is shown a shoe-protector comprising a toe-cover and securing-straps. The toe-cover consists of a bottom piece or sole 5, of leather, substantially semi-elliptical in shape 40 to correspond to the front portion of the sole of the shoe, and secured to the curved edge portion of this sole 5 is a soft-leather member 6 in the shape of a shoe-tip and which when the protector is in place upon the toe of the 45 shoe fits over the top of the latter, the toe of the shoe being received snugly between it and the sole portion 5. The sole portion 5 is tapered vertically at its rear edge portion, so that when in place on a shoe it will not form

an abrupt ridge and be uncomfortable, and 50 this rear edge portion has a binding 8, of sheet-brass or other suitable metal. The front portion of the member 6 has a tip 8, of sheet-brass or other suitable metal, which extends downwardly and is lapped over 55 against the bottom of the sole and serves to prevent cutting of the leather tip.

Fastened to the rear portions of the sides of the member 6 are straps 10 and 11, of which the former is sufficiently long to pass 60 along one side of the shoe and around the back and as far as the instep on the opposite side. The strap 11 is provided with a buckle 12 at its free end and is of such length that the strap 10 may be engaged with the buckle 65 to hold the protector upon the toe of the shoe. A third strap 16 is attached to the strap 11 at the buckle and is attached to the strap 10 at the same distance from the sole of the protector, the free ends of the strap 16 being 70 both above the straps 10 and 11 and one of these free ends having a buckle 17 for engagement by the other free ends, so that the strap 16 may be fastened firmly around the instep 75 of the shoe and will hold the straps 10 and 11 from slipping downwardly.

From the above it will be understood that the present article may be easily and quickly attached to a shoe and removed therefrom and that when in place it will protect the 80 shoe from injury at the toe.

It will be noted upon reference to Fig. 2 of the drawings that the bottom edge of the upper member 6 of the tip is let into the edge of the sole 5 and that the metal tip is against 85 the outer face of the sole, so that the parts are held securely together, and no insole is necessary to give a smooth inner surface to the sole.

What is claimed is—

90 A shoe-protector consisting of a sole, the rear edge portion of the sole being tapered, a metal binding secured upon the rear edge portion of the sole, an upper member let into the front and side edges of the sole, a metal 95 tip secured over the front portion of the upper member and against the bottom of the front edge of the sole, straps secured immov-

able to the inner rear edge portion of the upper member at opposite sides thereof, one of said straps having a buckle for engagement by the other strap, and a strap secured to opposite inner faces of the first-named strap with its free end portions above the latter and a buckle at one free end of the last-named strap arranged for engagement by the other

free end, said second strap also extending beneath the first strap.

In testimony whereof I affix my signature in presence of two witnesses.

F. N. PATTERSON.
